UNITED STATES PATENT OFFICE.

JAMES H. DOWNEY, OF GAINESVILLE, GEORGIA.

OPERATING-TABLE.

No. 876,044.

Specification of Letters Patent.

Patented Jan. 7, 1908.

Application filed March 19, 1907. Serial No. 363,308.

To all whom it may concern:

Be it known that I, JAMES HENRY DOWNEY, a citizen of the United States, residing at Gainesville, in the county of Hall and State 5 of Georgia, have invented a new and useful Operating-Table, of which the following is a specification.

This invention relates to surgical operating tables, and has for its principal object to provide a device of very simple construction which may be adjusted to position for exercising traction force in any direction in orthopedic work or for the purpose of reducing fractures or dislocations of the limbs or other 15 parts of the body, and for holding the parts in place during bandaging or the application of any dressings, plaster of paris, or the like.

A further object of the invention is to provide a device of this character in which the 20 necessary pull may be exerted, and the parts firmly held without danger of slipping or relaxing until the operation is completed.

With these and other objects in view, as will more fully hereinafter appear, the invention 25 consists in certain novel features of construction and arrangement of parts, herein-after fully described, illustrated in the accompanying drawings, and particularly pointed out in the appended claims, it being 30 understood that various changes in the form, proportions, size and minor details of the structure may be made without departing from the spirit or sacrificing any of the advantages of the invention.

35 In the accompanying drawings:—Figure 1 is a perspective view of an operating table constructed in accordance with the invention. Fig. 2 is a plan view of the same showing in dotted lines a number of positions to 40 which the various parts of the traction apparatus may be adjusted. Fig. 3 is a side elevation of the table showing the position of the parts as adjusted for a direct upward pull. Fig. 4 is a detail sectional view of a 45 portion of the windlass or winding mechanism. Fig. 5 is a detail view of one of the clamps. Fig. 6 is a detail sectional view of one of the table sockets and clamps.

Similar numerals of reference are employed 50 to indicate corresponding parts throughout the several figures of the drawings.

The main frame of the table is preferably formed of iron or steel rigidly braced throughout, and including vertical, or approximately vertical, end members 10 and 11

and side rails 12. To the frame of the table is secured a post 15 carrying a seat 16, and the post further carries a clamp 17 which may be used to clamp and hold the pelvis in position during certain operations. The table is so 60 arranged that the supporting surface may remain perfectly horizontal, or its various parts may be adjusted for the purpose of inclining the back, or the leg and for holding any part of the body in a position most convenient for the surgeon. In the present instance each of the leg supports is formed of two sections 18 and 19, the section 19 being arranged to receive the upper part of the leg and the section 18 the lower part thereof, and 70 these sections are pivotally connected together in order that the limb may be flexed as desired, and one or both sections may be dropped from under the limb or the back may be telescoped to give access to the patient while dressing around fractures and various orthopedic cases.

The principal feature of the invention, however, is the traction apparatus, and to receive this, the table is provided with four 80 sockets 20, 21, 22 and 23, there being one of such sockets at each corner of the table. These sockets are arranged for the reception of a pair of vertically disposed pins 25, which are held in place by cam levers 26 pivoted on 85 the socket members, as shown in Fig. 6, for the purpose of preventing upward movement and displacement of the pins from the socket.

On the upper end of one of the pins 25 is pivoted a rod 28, said rod having a reverse 90 bend at a point adjacent to its pivotal connection, so that the body portion of the rod may, if necessary, be adjusted to a point below the top of the table, and pivoted to the other pin 25 is a rod 29, that is bent in a 95 similar manner.

Near the outer end of the rod 28 is a sleeve 30 that is free to slide in the direction of the length of the rod, and said sleeve carries a clamping screw 31 by which it may be locked 100 in any position of adjustment. This sleeve carries ears 32 to which is pivoted one end of a tube 33, and the tube is telescoped on the rod 29 in order that the distance between the sleeve 32 and the pivoted end of the rod 29 105 may be increased or diminished when desired. The inner end of the tube 33 is provided with a rigid collar 34 carrying a clamping screw 35 which may be forced against the rod 29 for the purpose of locking the tube and rod to 110

gether and thus forming in connection with the rod 28 an angular truss of considerable strength and rigidity.

It will be seen that by loosening the screws 31 and 25, the angular relation of the two arms of the frame may be varied to a considerable extent, so that the apex of the frame may be drawn to one or other side of the longitudinal axis of the table, or may be maintained in such axial line as required, and when once adjusted, the frame may be locked in place by turning the screws. This construction permits of a considerable range of adjustment in a horizontal plane, while the 15 pivotal connections of the frame with the pins 25 permits swinging adjustment in a vertical plane, so that the frame may be moved to a vertical position, or to any angle between the vertical and horizontal, or to some extent 20 below the horizontal plane.

In order to firmly lock and hold the frame in adjusted position, a bracing member is employed, this, in the present instance, comprising a telescopically fitting tube 38 carrying a 25 collar 40 through which extends a clamping screw 41 which may be turned tightly against the rod. The outer end of the tube 38 is pivotally connected to an ear projecting from a sleeve 42 which may be adjusted in the direction of the length of the rod 28, while the lower end of the rod 39 is pivoted on a pin 43, said pin being swiveled in a clamp 44 that is arranged to embrace any desired part of the frame of the table, thus as shown in Fig. 1 the 30 clamp may be firmly secured to the vertical leg 10 of the table, or as shown in Fig. 3 it may be secured to one of the horizontal bars 12.

On the outer end of the rod 28 is a block 50 40 which may be adjusted both longitudinally and circumferentially of the rod and locked in place by a clamping screw 52. On this block is pivoted a small frame 53 which carries a short shaft 54 on which is mounted a 45 ratchet wheel 55 and winding drum 56. Pivotally mounted on the end or ends of the shaft 54 is an operating lever 58 carrying a pawl 59 arranged to engage the teeth of the ratchet wheel, and the ratchet wheel is held 50 from return movement by a small lock pawl 60 that is pivoted on the frame 53.

To the winding drum is secured one end of a flexible cord or chain 62 which may be connected in any desired manner to the part on 55 which traction force is to be exerted, and by operating the lever 38, the cord or chain 62 may be wound up and the limb or other part of the body stretched to reduce the fracture or dislocation, or for any other desired purpose.

The several sockets 20, 21, 22 and 23 are so arranged that the pivot pins may be placed in any of them, and the traction frame may thus be adjusted at either end or either side 65 of the table, while the adjustability of the

members of the frame permits the placing of the windlass at any point for the purpose of exercising a pulling strain in any direction.

When the parts are adjusted to the position shown in full lines in Fig. 2, a straight out pull may be exerted in a direction at a right angle to the longitudinal axis of the table, or if adjusted to the dotted line position *a*, a straight out pull may be exerted on the left arm of a patient, as for instance in 70 the reduction of a fracture or dislocation of the radius, ulna, humerus. When adjusted to the position shown by dotted lines *b*, in Fig. 2, longitudinal strain may be exerted on the spine. When adjusted to the dotted line 75 position *c* traction force may be exerted in the direction of the length of the right arm. The dotted line position *d*, Fig. 2, is exactly the opposite of that indicated in full lines in the same figure. The dotted line position *e* shows the adjustment which will permit 80 pulling strain on the right leg at a slight angle to the longitudinal axis of the table. The remaining two dotted line positions *f* and *g* show adjustments which will permit direct 85 pulls on both legs in a direction parallel to the length of the table.

When the parts are adjusted to the position shown in Fig. 1, a slight upward pull in the direction of the length of the table may 95 be exerted, and when the parts are moved to the position shown on Fig. 3, a direct vertical pull may be obtained.

The slideable connections of the various parts permit of an almost indefinite number 100 of adjustments, so that traction force may be exerted on practically any part of the body and in practically any direction, and when the bones have been brought into proper position they may be firmly held without danger 105 of release or displacement during the application of any dressing or drying of plaster casts, etc.

The apparatus will further serve as a means for rigidly supporting the limb or 110 other part of the body during the temporary removal of portions of the surface of the table, as for instance, the leg or back rest, so that bandages may be readily wound around any part of the body without the necessity of lifting or moving the patient in any manner.

I claim:

1. The combination with a surgical table, of a truss frame comprising a plurality of 115 slideably and pivotally connected members adjustable to varying angular positions with respect to each other and to the table, and a traction apparatus supported by said frame.

2. The combination with a surgical table, of a truss frame comprising a pair of main 120 truss members, one of which is slideably and pivotally connected to the other, means for locking said members in adjusted position, and a traction apparatus supported by the frame.

3. The combination with a surgical table, of a truss frame including a pair of main truss members, both of which are swiveled to the frame, the members being slidably and pivotally connected, and one of said members including a plurality of telescopic sections, means for rigidly locking the parts of the frame in adjusted position, and a traction apparatus supported by the frame.
4. The combination with an operating table, of a truss frame including a pair of main members swiveled to the table and adjustable to varying angular positions with respect thereto, a collar to which one of said members is connected, the collar being slidably mounted on the other member, means for rigidly locking the parts in any position of adjustment, and a traction means supported by the frame.
5. The combination with an operating table, of a traction apparatus including a truss frame, the members of which are adjustable with respect to each other and the table, a bracing bar for locking the frame to the table, and a traction means supported by the frame.
6. The combination with an operating table, of a truss frame comprising a pair of members having both pivotal and slidable connection, said members being adjustable to varying angular positions with respect to the table and to each other, means for locking the members of the frame in adjusted position, and a bracing bar adjustably connected to the frame and arranged for connection to various parts of the table.
7. The combination with an operating table, of a traction apparatus including a frame, and a plurality of frame connections arranged at different points around the table to permit adjustment of said frame to varying angular positions at both sides and both ends of the table.
8. An operating table having sockets at or adjacent to each corner, pins arranged to fit within said sockets, a truss frame pivoted to said pins, and a traction means supported by the frame.
9. The combination with an operating table, of a truss frame including a main rod swiveled to the table, a second rod, and a bracing rod, both of which are adjustably connected to the main rod, said second rod and bracing rod being each formed of telescoping sections, means for locking all of the parts in adjusted position, and a traction means supported by said main rod.
10. The combination with an operating table having sockets at or near each corner, of pins arranged to fit within said sockets, a main rod, and an auxiliary rod pivoted to said pins and rebent to extend below the upper surface of the table, a tube telescopic on the auxiliary rod, means for locking the tube and auxiliary rod together, a sleeve to which said tube is pivoted, the sleeve being slidable on the main rod, means for locking the sleeve to the main rod, a bracing member formed of telescoping sections, one of said sections being adjustably connected to the main rod, a table clamp to which the opposite end of the bracing rod is connected, and a traction means supported by said main rod.
11. The combination with an operating table, of a truss frame, a traction apparatus including a block having both swinging and longitudinal adjustment with respect to the frame, and means for locking the parts in adjusted position.
12. The combination with a surgical table, of an adjustable frame, a traction frame adjustably secured thereto, a shaft mounted in the traction frame, a ratchet wheel and winding drum on said shaft, an operating lever having a pawl engaging the ratchet wheel, and a locking pawl also engaging said ratchet wheel and tending to prevent return movement thereof.
- In testimony that I claim the foregoing as my own, I have hereto affixed my signature in the presence of two witnesses.
